HOCKEY GAME

Donald H. Munro, Toronto, Ontario, Canada

Application February 27, 1943, Serial No. 477,351

2 Claims. (Cl. 273—85)

My invention particularly relates to certain new and useful improvements in a game of the character disclosed in Letters Patent No. 2,048,944 issued to Ralph E. Grieve and myself on July 28, 1936. The game as described in said patent comprehends a board having a playing surface providing inclined fields sloping toward operating ends. The device is a parlor game simulative of hockey and has goals at its ends defended by goalkeepers in the form of bodily swingable game pieces manipulated by the players. A ball such as a marble is used in lieu of a puck, and is put in play by projectors. Flicking devices are swingably mounted upon the playing surface for manipulation by the operators to score a goal. The flicking devices represent the hockey men of opposing teams; all the men of each team being concurrently actuated by a manually controlled element. The course of the game piece in gravitation toward a goal is influenced by the arrangement of hazards. So soon as the game piece rolls to an end of the playing surface the play is brought to a finish and the game piece must be again projected to put it into play.

According to my present invention as set forth in the ensuing specification I have devised an important and highly advantageous improvement relating to the structure of the ends of the playing board by which the play is not necessarily brought to an end when the game piece rolls to an end of the playing surface.

The structure comprises the provision of an end wall curved outwardly and forwardly from a point behind a goal in an encircling manner with the curvature at one side prolonged and directed inwardly. The inwardly directed extent of the curvature has an inclined end face. In conjunction with the compound curvature I arrange a flicker at an angle therewith having its free end in close proximity thereto so as to swing outwardly toward the goal when actuated.

According to this arrangement, when the game piece gravitates or is shot between the goal and either of the flickers thereat belonging to the rival team the curved end wall causes the game piece to roll from one side to the other. By shifting the flickers so as to open the one at the compound curvature the game piece will roll past it and can be caught and then shot toward the goal or the opposite flicker, thus keeping the game piece in play with the object of scoring a goal. Again, the game piece may be caught directly between the compound curvature of the end wall and the flicker thereat, in which event the play may be continued.

This feature makes the game far more exciting and fascinating. Additionally, both skill and judgment are required in the execution of the plays.

6 Referring to the drawing,

Fig. 1 is a plan view of the game showing the flickers in their normal positions, the positions to which they may swing being indicated in dash lines.

10 Fig. 2 is a side elevation of Fig. 1 showing the end portions in section.

Fig. 3 is a plan view of the mechanism below the playing surface of the game board by which an operator manipulates one set of flickers from 15 a playing end. It will be understood that there is a similar mechanism for the other set of flickers.

Fig. 4 is a fragmentary plan view of the game showing one end thereof with flickers shifted 20 from their normal positions.

Fig. 5 is a sectional detail taken on line 5—5 of Fig. 1.

Like numerals of reference indicate corresponding parts in each of the figures throughout 25 the drawing of the invention.

My invention is illustrated in the drawing as appertaining to a game comprising an elongated board having a playing surface divided by a median line 6 into two playing fields 7 and 8, each 30 planar and sloping toward the ends 9 and 10 so that when a marble 11, which is used to present a puck, is put into play by a projector 12 at one end of the board it will traverse the median line 6 or crest of the playing surface and gravitate 35 toward the other end. The runway of each projector is shown as supplied with a flexible deflector 13 arranged to block the exit so that the marble may not return. The goals 14 and 15 are in the form of nets and are defended by goalkeepers 16 and 17 respectively, each in the nature of a peg mounted on an axis for lateral movement by means of a lever handle 18 manipulated by a person in playing the game. Each person or operator plays from an end of the board 40 45 as will be understood. Deflectors as at 19 may be arranged in spaced relation to the runways of the projectors 12.

Each team of hockey men is represented by a set of flickers on the playing field. One set comprises the members A, B, C, D and E, which are 50 operated concurrently by the handle 20. The other set comprises the members A', B', C', D' and E', which are operated by the handle 21 at the other end of the board.

55 The flickers are arranged as shown in Fig. 1

and it will be observed that the members A and B of one set flank the opponent's goal, and that the members A' and B' of the other set are correspondingly disposed with respect to the other goal. The members D and E, and also the members D' and E' provide for direct goal shots. The members C and C' provide for checking and passing et cetera, and constitute hazards in the playing of the game. The members A and B and the corresponding members A' and B' are used for goal shots as will be understood by anyone familiar with the game.

As best shown in Fig. 5, each flicker consists of an arm 22 of wire rod material journaled by an axis 23 at one end by which it is swingably mounted on the board. The arm has an integral lever 24 at the underside of the board by which it is actuated. A peg 25 represents a man, and the pegs of one team are of a different color to those of the other team for distinguishing purposes. The lever 24 of the flickers A, B, C, D and E are connected by wire rods as at 26, Fig. 3 to the handle 20 for concurrent action. The rods 26 are spring urged to retain the flickers in normal position. The other set of flickers are controlled by a similar mechanism attached to the handle 21.

Since the playing board is symmetrical about its centre line, a description of one end, in regard to the improved features, will serve for both. The end 10 is provided with a wall 27 having a curved face 28 which sweeps inwardly and forwardly from behind the goal 15 toward opposite sides of the board in a manner to encompass the flickers A' and B'. The flicker B' is normally disposed with its arm extending away from the adjacent side of the goal on a slight forward angle so that the marble can be flicked toward this goal. The curved face 28 terminates at the right hand side of the board at a point in proximity to the distal end of the flicker B', but at the left side thereof it is curved inwardly, as at 29, about the axis of the flicker A' on a reduced radius such as will serve to deflect the marble forwardly in the general direction of goal 15. Wall 27 has a deflector face 30 sloping upwardly from the end of curvature 29 and meeting the adjoining side wall of the board. The arm of flicker A' is positioned to extend rearwardly from its

axis to meet the curved face 28 so as to form therewith a pocket 31 in which the marble may lodge.

In playing the game it will be found that the marble will on occasions directly roll into the pocket 31, or be guided into the same by the deflecting face 30. When this happens the operator can make a goal shot by driving the marble out of the pocket with a short, quick flick of the flicker A'. When the operators lose control of the marble in a play and it hits the wall 27, the curved face 28 causes it to roll from side to side. The marble can then usually be caught by swinging the flicker A' slightly away from this curved face to permit the marble to pass into the pocket, as indicated in Fig. 4. The flicker is then released and subsequently operated to drive the marble toward the goal.

Having exemplified the function of my improved structure, it is not necessary to describe all the plays that can be made, but it will be manifest that the invention presents an important improvement in the art.

What I claim is:

1. In a game apparatus comprising a generally rectangular board, the playing surface of which slopes toward opposite ends thereof, a continuous game piece retaining and directing wall surrounding the playing surface of the board, goals arranged on the inclined playing surface adjacent the end walls of the board, and means movably mounted on the playing surface for controlling the movement of the game piece thereover, the inner surface of each end wall being continuously curved from side to side of the board behind a goal and in spaced relation thereto, one end portion remote from the goal of each of said continuously curved surfaces being further curved forwardly and inwardly toward the longitudinal center of the board and to a point in advance of the entrance to the goal.

2. The structure of the game apparatus as defined in claim 1, wherein a reentrant angle wall portion joins each of the inwardly curving end wall portions to an adjacent side wall of the board forwardly of the entrance to the respective goals for deflecting a game piece inwardly towards the longitudinal center of the board.

DONALD H. MUNRO.
